UNITED STATES PATENT OFFICE.

CHARLES FISCHER, OF NEW YORK, N. Y.

SCREEN FOR TELEPHONES.

Application filed September 17, 1924. Serial No. 738,320.

My invention relates to a wire-frame telephone screen adapted to be covered by any suitable material, for example, silk, and more particularly to such a screen provided 5 with wire clamps to be clamped to the telephone to be screened, said clamps being constructed so that they may be firmly secured to the wire frame without soldered or welded joints, thus eliminating the breakage due to 10 the use of such joints.

One of the objects of my invention is to provide a wire-frame telephone screen to be covered with a suitable fabric of any desired color or shade, the frame and cover although 15 effectively screening the telephone from view when not in use, being shiftable, thus permitting ready access to the telephone without lifting the screen from the telephone.

Another object of my invention is to provide 20 such a screen with a number of wire clamping members which are firmly secured to the wire frame of the screen, and whose clamping portions are constructed so as to yield when pressed against the telephone and 25 permit the telephone to be easily yet tightly clamped.

With the above and other objects in view, my invention consists in the parts, improvements and combinations more fully pointed 30 out hereinafter.

Referring now to the drawings:

Figure 1, illustrates a front view of the screen, showing the telephone in place behind the screen.

Figure 2, is a top plan view on line 2—2 of Figure 1, looking down at the screen and telephone, the dotted lines showing the position of the screen when turned to permit use of the telephone.

Figure 3, illustrates one of the wire clamps for clamping the screen to the telephone.

Figure 4, is a perspective view showing the screen and clamps without the telephone in place and with the cover for the screen 45 removed, and

Figure 5, is a sectional side view of the screen and cover, on line 5—5 of Figure 2, showing the screen clamped to the telephone.

In the drawings, the numeral 1 designates 50 the telephone to be screened. The wire frame of the screen consists of the upper and lower cross bars 2, 3, which may be of any desired form, but which are preferably shaped so as to form the front and side cross bars for the frame, and the upright bars 4,

5. The wall thus formed partially sur-

rounds the telephone stand sideways and can be shifted laterally when the telephone is to be used. Vertical bars 6, 7, mounted midway of the width of the frame and horizontal cross-bar 8, mounted midway of the length of the frame, help to make the screen of rigid construction and form a support for the clamping members. The frame or wall is semi-cylindrical and its height is substantially that of the telephone. The clamping members are each made in one piece, in the best embodiment of the invention. Each clamping member consists of two inwardly projecting arms 9, 10, which space the screen 60 from the telephone and project inwardly between the top and bottom of the frame. One end of each arm is provided with a loop 11, 12, which loops encircle the vertical bars 6, 7, extending lengthwise in the wire frame, 65 the loops being connected by a cross-piece 13. A plate 14 is provided for each clamping member and has bent ends 15, 16. In the form of the invention illustrated, the end 15 of one plate receives the cross-piece 13 70 of the arms of one clamping member and the end 16 fits tightly around the cross-bar 8 of the frame. The bent end 15 of the other plate surrounds the cross-piece 13 of another clamping member and its other bent end 16, 75

is attached to the cross-bar 8, forming the bottom of the screen. The provision of loops 11, 12, in the arms of the clamping members for engaging the vertical bars of the frame, and the plate 14 attached to each cross-piece 80 of a clamping member and to a cross-bar of the screen, constitute a firm supporting means for the clamping members. The strain of supporting the clamping members on the frame is thus distributed. This construction does away with soldered joints and the like and breaking of the clamping member from the screen is less likely to occur. 85

The two arms, 9, 10, of each of the clamping members are widest apart at the point 90 where they are attached to the frame and converge as they project inwardly until they almost meet. Each arm is provided, at its inner end, with a bent portion 17, 18, having hooked ends, 19, 20. The bent portions of the arms, together with their hooked ends, 100 form the clamping means, which receive and hold the telephone. The construction of these hooked end is such, see Figure 4, that it is not necessary to open the clamp by hand before the telephone can be clamped. The pressure of the telephone against the 105 110

hooked ends of the clamp will cause them to yield, and the clamp will open outwardly and permit the telephone to enter the bent loop-shaped portion of the clamp. After 5 the telephone has thus entered the loop-shaped portion, the hooked ends will return to substantially normal position and hold the screen tightly and frictionally clamped to the telephone, at the same time permitting 10 the movement of the screen about the telephone.

The construction of the arms of the clamping members, widest apart at the supporting end and nearest together at the clamping 15 portion, permits the yielding action of the clamp, opening to receive the telephone, to be effected without undue strain on the clamping member.

The operation of the screen will now be 20 described. The screen with its wire clamps is placed in front of the telephone and is pressed against the instrument. The hooked ends of the clamping members will yield and permit the clamp to open outwardly sufficiently to allow the telephone to enter the 25 loop-shaped portion of the clamp, after which the hooked ends will return to normal position and tightly clamp the screen to the telephone. When it is desired to use 30 the telephone, the screen is turned sideways, in a direction opposite to the side of the telephone on which the receiver is mounted, and the telephone is quickly and readily accessible. It is not necessary to remove the 35 screen before using the telephone. After using the telephone, the screen is again turned back into place.

Having thus described the invention and its operation, it will be understood that 40 changes may be made in carrying the invention into effect, without departing from the principle thereof.

What I claim is:

1. A shiftable screen for telephones comprising a semi-cylindrical wire wall having 45 a front portion adapted to extend in front of the telephone stand, said wall extending sideways partially around the telephone stand, a plurality of wire clamping members 50 with normally separated ends, and means for attaching the clamping members one above the other to said wall, said members spacing said wall from the telephone stand and projecting inwardly from the wall, intermediate the top and bottom thereof, the clamping portions of said members being constructed so as to yieldingly engage the 55 telephone stand.

2. A shiftable screen for telephones comprising a wire frame wall having a vertical 60 wire member extending across the front of the frame, said wire frame wall extending in front of and partially around the telephone

stand, a wire clamping member and means for attaching the clamping member to said vertical wire, the clamping portions of said member comprising wire arms with loop-shaped normally separated ends which yield so as to open and engage the telephone stand. 65

3. A screen for telephones comprising a wire frame, a plurality of yielding clamping members, each member being composed of one piece and having two inwardly projecting arms, each arm separated from the other, but the arms converging toward each other, 70 one end of said clamping members constructed so as to form the clamping portion, the other end of said clamping members terminating in a cross-piece, and a plate attached to said cross-piece and to said wire frame for securing the clamping members 75 to the frame.

4. A screen for telephones comprising a wire frame, having top and bottom cross-bars, a pair of wire members, one end of each member forming a yielding clamping portion to receive the telephone, the other end of each member being provided with means for attaching it to the frame, two vertical bars mounted in and extending the entire 80 length of said frame and a cross-bar mounted midway in said frame, means for securing one of said clamping members to said vertical bar and the central cross-bar, and means for securing the other clamping member to the vertical bars and the cross-bar 85 forming the bottom of the frame. 90

5. A screen for telephones comprising a wire frame, a plurality of yielding clamping members, and vertical bars mounted in 100 the front of said frame to support the clamping members, one end of said members forming the clamping portion for the telephone, the other end of said members being provided with loops, said loops encircling the vertical 105 bars of said frame.

6. A screen for telephones comprising a wire frame, a plurality of yielding clamping members, each member consisting of two arms, one separated from the other, said frame being provided with vertical bars and cross bars for supporting the clamping members, one end of said members forming the clamping portion, the other end having loops 110 which surround the vertical bars, a wire cross-piece connecting the arms of each clamping member, and a plate with bent upper and lower portions, one of said bent portions receiving the cross-piece of said clamping members and the other secured to 115 a cross-bar of the frame to secure the clamping member to said frame. 120

In testimony whereof, I have signed my name to this specification.

CHARLES FISCHER.
